UNITED STATES PATENT OFFICE

JAMES S. JUERGENS, OF MORGANTOWN, WEST VIRGINIA

GENERATOR REGULATOR

Application filed September 20, 1929. Serial No. 394,115.

The present invention relates to a regulator for generators and especially generators of relatively small capacity such as are employed for charging storage batteries in automobiles and other electrical systems.

5 An object of the invention resides in the general improvement of such structures so as to lower the cost of manufacture as well as to make practical the use of the apparatus by 10 eliminating corrosive action on parts and contact points.

A further object of the invention consists in the provision of such a regulator which is reliable in operation, contains no parts liable 15 to become disorganized, and is provided with a hydraulic stabilizer to prevent variations in the rate of charging the battery, which would otherwise be caused by reason of road shocks.

Other objects and advantages of the invention will be apparent from the following description when taken in connection with the accompanying drawings, in which

Figure 1 is a perspective view of the complete apparatus.

25 Figure 2 is a vertical sectional view through the hydraulic stabilizer and variable resistance coil; a portion of the float being broken away.

Figure 3 is a horizontal sectional view taken 30 on line 3—3 of Figure 2, a part of the core being broken away.

Figure 4 is a vertical sectional view through the variable resistance coil and associated parts.

35 Figure 5 is a side elevational view of a battery employed in the system, parts being broken away to more clearly show the construction; and

Figure 6 is a fragmentary sectional view 40 taken on line 6—6 of Figure 5.

Referring to the drawings in greater detail, the numeral 1 indicates a conventional type of secondary or storage battery, except that it is formed with a float compartment 2 preferably in the battery cell of the positive terminal provided by means of a partition 3. This partition is formed with a plurality of perforations 4 which permit free passage of the electrolyte from the adjoining cell into 45 the float compartment.

Mounted in the float compartment 2 is a float 5 of ample proportions to respond appreciably to variations in the specific gravity of the electrolyte. This float, as indicated, is in the form of a solid bakelite, hard rubber, asphalt or other non-corrosive substance, and has fixed to its upper surface a rod 6, pivotally connected at its upper end to an arm 7 as by means of the pin and slot connection 8. The opposite end of the arm 7 is pivotally connected to brackets 9 secured to the block 10 for the hydraulic stabilizer and resistance coil.

Within the block 10 are provided the cylindrical compartments or receptacles 11 and 12 which are connected at their lower and upper ends by passages 13 and 13' of small cross-section. Within these compartments is placed a quantity of oil as by means of a charging opening 14. It will be apparent that the oil may pass from one compartment to the other, but that this transfer cannot take place at a rapid rate due to the small capacity of the passages 13 and 13'. By reason of this arrangement movements of the variable resistance, about to be described, are damped, and thus irregularities in the charging rate of the battery due to road shocks and the like are prevented.

55 Suspended from the arm 7 by pin and slot connection 15 is a rod 16 which carries at its lower end a plunger 17 of rubber, bakelite, or other non-conducting material. This plunger is situated in the compartment 12 of the stabilizer mechanism and is immersed in the oil in this compartment, and forms a core on which is spirally wound a resistance wire 18. This wire may be of round or flat cross-sectional shape and is preferably imbedded in the material of the plunger as indicated in Figure 4. Cooperating with the resistance wire 18 is a pair of spring pressed brushes 19 which are connected in the circuit of the field coil 20' of the generator 20 by means of the wires 21 and 22. Pressure of the brushes on the resistance coil may be adjusted by means of the screws 23 which vary the compression on the springs 24 in engagement with the inner ends of the brushes.

95 100 The oil bath above referred to in connec-

tion with the variable resistance also serves as a means for preventing corrosion of the brushes 19 inasmuch as they are immersed in oil at all times.

- 5 For the purpose of insuring a minimum resistance in the field coil circuit when the battery is discharged or only partly charged, a compression spring 25 encircles the rod 16 and has its ends bearing on the top of the
 10 plunger 17 and the upper wall of compartment 12 respectively, thus tending to return the plunger to its lowermost position with respect to the brushes 19 and placing a minimum amount of the coil 18 in the field coil
 15 circuit.

In the operation of the device, the electrolyte in the battery cell of the positive terminal is allowed to freely circulate through the float compartment 2 by reason of the perforated partition 3. As the specific gravity of this liquid increases the float 5 will rise proportionately and in so doing will raise the arm 7 upwardly about its pivot on brackets 9. This raising of arm 7 will lift the plunger
 20 17 and the resistance coil wound thereon, thereby cutting in a greater portion of the resistance wire 18 to the field coil circuit and decreasing the current generated in the armature of the generator with a consequent
 25 decrease in the rate of charge entering the battery. As the plunger is raised in its compartment 12 it displaces less of the oil therein and a flow of this fluid takes place from compartment 11 through passage 13 to compartment 12. This presence of a full quota of liquid in the compartment prevents a sudden depression of the plunger by road shocks since the narrow passage 13 will not admit of a quick discharge of the liquid there-
 30 through, and consequently serves to stabilize the position of the coil and prevent substantial variation in the rate of charging the battery which would otherwise be caused when traveling over rough roads.

40 45 As the battery becomes more or less discharged and the specific gravity of the electrolyte is reduced the float 5 will sink lower in compartment 2 and in so doing will lower the plunger 17 in compartment 12. Down-
 50 ward movement of the plunger 17 is assisted by the coil spring 25, and the passages 13 and 13' serve to transfer excess liquid from the compartment 12 to compartment 11 in response to the lower position of the plunger.
 55 The lowering of the plunger 17 cuts out a substantial part of the resistance coil 18 from the field circuit of the generator and thereby causes an increase in the rate of current generation and a more rapid charging of the
 60 battery.

From the foregoing description taken in connection with the accompanying drawings it will be apparent to those skilled in the art that I have devised an exceedingly simple
 65 construction for automatically regulating a

variable speed generator of the automobile type, which contains no mechanisms liable to become disorganized; that the variation in the rate of charging the battery is controlled by variation in the specific gravity of the electrolyte of the battery; that the parts will be maintained free from corrosion; that the apparatus is not affected by road shocks; that it requires no adjusting; and that due to its simplicity of design may be produced at a minimum cost.

In accordance with the patent statutes I have shown and described what I now believe to be the preferred form of the invention, but inasmuch as minor changes may be made in the details of construction without departing from the spirit of the invention it is intended that the drawings be considered as illustrative of the invention rather than in a limiting sense.

What I claim is:

1. A generator controller for automobiles, including a secondary battery, a float disposed in the electrolyte of said battery, a generator, a variable resistance coil in the field circuit of said generator, an operative connection between the float and variable resistance coil for adjusting the latter, and a stabilizer for preventing the transmission of road shocks to said resistance coil.

2. A generator controller including a secondary battery, a float disposed in the electrolyte of said battery, a generator, a variable resistance in the field circuit of said generator, a movable plunger on which said resistance is mounted, a connection between said float and plunger, and a hydraulic stabilizer associated with said plunger.

3. A generator controller including a secondary battery, a float disposed in the electrolyte of said battery, a generator, a variable resistance coil in the field circuit of said generator, a movable plunger on which said resistance coil is mounted, an oil bath for said plunger and resistance coil, and a connection between said float and plunger.

4. A generator controller including a secondary battery, a generator, a variable resistance in the field circuit of the generator, means associated with the battery for adjusting the variable resistance in accordance with the condition of the battery, and an oil bath in which said variable resistance is mounted.

5. In a generator controller, a variable resistance in the field circuit of the generator, said variable resistance including a plunger on which a resistance coil is wound, an oil bath in which the plunger is reciprocably mounted, and means for permitting a gradual movement of the oil to and from said bath as movement is imparted to the plunger.

J. S. JUERGENS.
